GERSTEIN & BORUN LLP

(57) **CLAIM**

The ornamental design for a tactile tile, as shown and described.

DESCRIPTION

FIG. 1 is a front view of a tactile tile of the new design; FIG. 2 is a bottom view of the tactile tile of FIG. 1; FIG. 3 is a right elevation view of the tactile tile of FIG. 1; FIG. 4 is a left elevation view of the tactile tile of FIG. 1; FIG. 5 is a top view of the tactile tile of FIG. 1; and, FIG. 6 is a rear view of the tactile tile of FIG. 1.

The evenly broken lines in the drawings depict portions of the tactile tile that form no part of the claimed design. The unevenly broken lines in FIGS. 1 and 6 depict the boundary of the claim that forms no part thereof.
